UNITED STATES PATENT OFFICE.

ARTHUR AUDET, OF CONCORD, NEW HAMPSHIRE.

ICE BUNKER.

Application filed February 8, 1923. Serial No. 617,812.

To all whom it may concern:

Be it known that I, ARTHUR AUDET, a subject of the King of England, residing at Concord, in the county of Merrimack and State of New Hampshire, have invented certain new and useful Improvements in Ice Bunkers; and I do declare the following to be a full, clear, and exact description of the invention, such as will enable others skilled in the art to which it appertains to make and use the same.

My invention relates to improvements in ice bunkers used in refrigerator cars and has more particular reference to bunkers of the type in which the inner wall of the bunker extends transversely of the car in spaced relation with one end wall thereof and terminates on a line spaced upwardly from the car floor to permit the insertion and removal of a drip pan which receives the drippings from the ice supported upon the usual or any preferred grating.

It is the principal object of my invention to provide a novel form of barrier and unique means for securing it in place between the inner wall of the bunker and the floor of the car, for the purpose of retaining the drip pan in place beneath the ice supporting grating, yet permitting quick and easy withdrawal of said pan whenever necessary.

With the foregoing in view, the invention resides in the novel subject matter hereinafter described and claimed, the description being supplemented by the accompanying drawings.

Figure 1 is a vertical longitudinal sectional view through one end of a refrigerator car equipped with a bunker constructed in accordance with the present invention.

Figure 2 is a vertical transverse sectional view as indicated by line 2—2 of Fig. 1.

Figure 3 is a horizontal sectional view on line 3—3 of Fig. 1.

Figure 4 is a fragmentary sectional view similar to a portion of Fig. 2 but cut, in part, on a different plane.

Figure 5 is a perspective view of the barrier which secures the drip pan in place.

In the drawings above briefly described, the numeral 1 designates one vertical end wall of a refrigerator car and the character 2 indicates the floor of the car. Spaced inwardly from the wall 1 and extending transversely across the car, is a wall 3 which contacts with portions of the car sides and the

end wall 1, in forming an ice bunker B, this bunker being suitably lined as indicated at 4 and being provided at its lower end with an ice supporting grating 5 which is spaced 60 above the floor 2.

In constructing the wall 3, I preferably mount a horizontal beam 6 transversely in the car in vertically spaced relation with the floor 2, secure a pair of upright studs 7 to 65 the sides of the car, suitably anchor intermediate studs 8 to the beam 6 and secure the upper ends of these studs to one of the usual roof supports 9, by means of bolts or the like 10. In the present construction, a spacing 70 bar 11 is interposed between the upper ends of the studs and the support 9.

By employing the construction just described, a rigid framework is provided for the wall 3 which will be sufficiently durable 75 to withstand all stresses, regardless of the fact that it does not extend entirely to the floor of the car.

An appropriate drip pan 12 is provided beneath the ice supporting grating 5 and 80 for the purpose of holding this pan normally in place and protecting it against injury due to possible shifting of the load within the car, I provide a transverse barrier secured detachably in place beneath the 85 wall 3. In the preferred form of construction, this barrier is in the form of a transverse beam 17 whose ends have mortise and tenon or other suitable connections with a pair of upright blocks 18. These blocks 90 project a slight distance below the bar 17 for reception in sockets 19 in the floor 2. The upper ends of the blocks 18 extend a greater distance from the bar 17 and are provided with openings 20 in which lag 95 screws 21 or other fasteners are received, for the purpose of securing the two blocks 18 to the sides of the car.

By securing the bar 17 in place in the manner above described, it will be seen that 100 this bar will secure the pan 12 in place and protect the same against injury, yet that by simply removing the two fasteners 21 and tilting the bar and its blocks 18 inwardly, said blocks may be entirely disengaged from 105 the sockets 19 and thus may be bodily removed to permit withdrawal of the pan.

Attention may be directed to the fact that the depending portions of the blocks 18 and the ends of the sockets 19 form co-acting 110 shoulders carried by the barrier 17 for holding its lower portion in place and the upper

2

portions of the blocks 18 form lugs through which the fasteners 21 pass. Obviously, equivalent parts could be substituted for these elements.

5 From the foregoing, taken in connection with the accompanying drawings, it will be seen that I have provided a simple and durable ice bunker which, while normally holding the drip pan in place and protecting the same, will permit quick and easy removal thereof when necessary. As excellent results may be obtained from the details disclosed, they are preferably followed, but within the scope of the invention as claimed, numerous minor changes may be made.

15 I claim:

1. A refrigerator car ice bunker comprising an inner transverse wall spaced from 20 one end wall of the car and terminating in vertically spaced relation with the car floor, a drip pan under the bunker removable by sliding it under said inner wall, a removable barrier for holding said pan in place, said barrier being interposed between the aforesaid inner wall and the floor of the car, co-acting means on the barrier and the car for securing the lower portion of said barrier in place, said means being releasable by outwardly swinging the upper portion of the barrier, and releasable means for securing the upper portion of said barrier normally against such outward swinging.

2. A refrigerator car ice bunker comprising 35 an inner transverse wall spaced from one

end wall of the car and terminating in vertically spaced relation with the floor of said car, a drip pan under the bunker removable by sliding it under said inner wall of the bunker, a barrier interposed between said 40 inner wall and the floor of the car for retaining said pan in place, co-acting shoulders on the barrier and the car floor for securing the lower portion of the former in place, lugs extending upwardly from said 45 barrier, and detachable fasteners passing through said lugs and engaging relatively stationary parts to secure the barrier in place.

3. A refrigerator car ice bunker comprising an inner transverse wall spaced from 50 one end wall of the car and terminating in vertically spaced relation with the floor of said car, a drip pan under the bunker removable by sliding it under said inner wall of the 55 bunker, a horizontal barrier bar resting on and extending transversely of the car floor under said inner wall of the bunker, vertical blocks secured to the ends of said barrier bar and extending both upwardly 60 and downwardly therefrom, the floor of the car having sockets removably receiving the lower ends of said blocks, and detachable fasteners passing through the upper ends of 65 said blocks and engaged with relatively stationary parts.

In testimony whereof I have hereunto affixed my signature.

ARTHUR AUDET.
